UNITED STATES PATENT OFFICE.

MARY FIELDING HAVENS, OF ENID, OKLAHOMA TERRITORY.

INCUBATOR.

SPECIFICATION forming part of Letters Patent No. 651,246, dated June 5, 1900.

Application filed November 13, 1899. Serial No. 736,829. (No model.)

To all whom it may concern:

Be it known that I, MARY FIELDING HAVENS, a citizen of the United States, residing at Enid, in the county of Garfield, Oklahoma Territory, have invented a new and Improved Incubator, of which the following is a full, clear, and exact description.

The object of the invention is to provide a new and improved incubator arranged to prevent possible injury or undue crowding to hatched chickens, the incubator requiring no lamp or other similar heating device, and for convenient shipment the incubator is made in knockdown style to allow the recipient thereof to readily set up the incubator without the aid of skilled labor.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a perspective view of the improvement with the water-heating tank and filling-piece removed. Fig. 2 is a similar view of the water-tank. Fig. 3 is a perspective view of the filling-piece, and Fig. 4 is a transverse section of the improvement on the line 4-4 in Fig. 1.

The improved incubator is provided with a box A, open at the top and having at the inside transverse partitions B B', connected with each other near the rear of the box by a longitudinal partition C, said partitions B, B', and C extending at their top and bottom edges a suitable distance from the top and bottom of the box, as is plainly indicated in the drawings. The partitions B B' are nailed or otherwise secured to the front and rear of the box, while the partition C is similarly fastened to the partitions B B'.

On the lower ends of the transverse partitions B B' are arranged transverse cleats or guideways B² for a drawer D to slide on, said drawer having a compartment D' for receiving the eggs to be hatched and the chickens after being hatched, the forward end of said drawer being formed with a compartment D², adapted to receive sand or similar material.

The compartments D' D² are separated from each other by a longitudinal partition D³.

Directly above the compartment D' is arranged a water-heating tank E, preferably made of metal, a filling-pipe E' extending upwardly from the top of the tank to allow of filling the same with hot water whenever desired. After filling the tank the upper end of the pipe E' is closed by a suitable cap E². A discharge-pipe E³ leads from the front lower end of the tank E and extends under a filling-piece F and through an opening A' in the front of the box. The outer end of the discharge-pipe E³ is normally closed by a stopper E⁴; but when it is desired to empty the tank of the water the stopper is removed to allow the water to flow out of the tank, and when the tank is empty the stopper is replaced and the tank is refilled with hot water to give the desired heat to the eggs in the compartment D' of the drawer D.

The upper end of the tank E is formed with an outwardly-extending flange E⁵, adapted to rest on the upper ends of the partitions B, B' and C, so that the tank is suspended in the box between the partitions B B' and adjacent to the partition C. By this arrangement the bottom of the tank forms a top for the compartment D' of the drawer D to uniformly heat the eggs and prevent the chickens from being injured when pulling the drawer out or from being unduly crowded.

The filling-piece F is held between the front end of the tank E and the front of the box A, and the sides of said filling-piece rest on suitable pins attached to the partitions B B'. This filling-piece is preferably covered on top by a sheet of paper F', extended up against the front of the box A and that of the tank E, to prevent the sand, sawdust, or other material filled into the box on the outside of the partitions on top of the tank and the filling-piece from slipping down into the drawer D. It is understood that when the tank E and the drawer D are in position the remaining parts of the box are filled with sand, sawdust, or the like, so that the compartment D' is protected against cold, and the heat radiating from the water-tank E is contained mainly in the compartment D to insure a proper hatching of the chickens.

In using the incubator hot water is first

filled into the tank E to heat the sand or other filling material as well as the drawer, and about twelve hours after the filling of the tank with water the eggs are placed in the 5 drawer. From this time on either all or only some of the water in the tank is replaced 10 every day by hot water until the chickens are hatched. If desired, the hatched chickens may be placed on the sand on the top of the box, which is then used as a brooder. In 15 case the temperature in the egg-drawer becomes too low it is necessary to temporarily remove the drawer D and to place the same over a pan filled with sand and heated in a stove to about 115°. By this arrangement the heat in the drawer is restored and the drawer is then replaced in the box. While 20 the drawer is heated outside the box, as described, the tank E is refilled with hot water to restore the heat in the box before returning the drawer.

Having thus fully described my invention, I claim as new and desire to secure by Letters Patent—

- 25 1. An incubator, comprising a box, drawer-guides in said box, a drawer arranged to slide in the box on said guides, and provided with a compartment for the eggs which is spaced from the box on all sides, a heating-30 tank in said box above the drawer, the said box being filled with sand or the like on all sides of the drawer and heating-tank, and a filling-cap in the box above the drawer and between the egg-compartment of the latter 35 and the front of the box, whereby when the drawer is withdrawn from the box the sand will be prevented from dropping into the egg-compartment of the drawer, as set forth.
2. An incubator, comprising a box open at the top and having transverse partitions extending from the front of the box to the rear thereof, the top and bottom edges of the partitions being a distance away from the top and bottom of the box, a longitudinal partition connecting the transverse partitions with each other a distance from the rear of the box, a drawer for the box, and held to slide on guide-ways on said transverse partitions, the top of the drawer being a distance below the top edges of the partitions, a water-tank having

a flange at its upper end to rest on said partitions and thereby suspend the tank in the box, the bottom of the tank being directly over said drawer, and a filling-piece extending from one transverse partition to the other, 55 substantially as shown and described.

3. An incubator, comprising a box open at the top and having transverse partitions extending from the front of the box to the rear thereof, the top and bottom edges of the partitions being a distance away from the top and bottom of the box, a longitudinal partition connecting the transverse partitions with each other a distance from the rear of the box, a drawer for the box, and held to slide on guide-ways on said transverse partitions, the top of the drawer being a distance below the top edges of the partitions, a water-tank having 60 a flange at its upper end to rest on said partitions and thereby suspend the tank in the box, the bottom of the tank being directly over said drawer, said tank having an upwardly-disposed filling-pipe and a forwardly-extending discharge-pipe reaching to the outside of the box, and a filling-piece be- 65 tween the front of the water-tank and the front of the box, the filling-piece extending over the said discharge-pipe from one transverse partition to the other, substantially as shown and described.

4. The herein-described incubator, comprising a box having transverse partitions spaced from the sides and top and bottom of the box and a similar longitudinal partition spaced from the rear of the box, a heating-85 tank adapted to fit in said partitions, a drawer fitted to slide on the transverse partitions below the tank and having an egg-compartment 90 at its rear and a compartment for sand at its front, the box being filled with sand on all sides of the heating-tank and drawer, and a filling-cap above the sand-compartment of the drawer and adapted to prevent the sand from falling into the drawer when the latter is withdrawn from the box, as set forth.

MARY FIELDING HAVENS.
